UNITED STATES PATENT OFFICE.

DANIEL MICHEL WEIGEL, OF LONDON, ENGLAND.

INTERNAL-COMBUSTION ENGINE.

Application filed August 4, 1919. Serial No. 315,135.

To all whom it may concern:

Be it known that I, DANIEL MICHEL WEIGEL, a subject of the King of Great Britain, residing at London, England, have 5 invented certain new and useful Improvements in Internal-Combustion Engines, of which the following is a full, clear, and exact description.

In my applications for patents No. 265,463 10 filed Dec. 5, 1918, No. 273,849 filed Jan. 29, 1919, and No. 308,632 filed July 3, 1919, I describe an engine of a rotary type provided with substantially radial cylinders revolving upon a central axis, the pistons being 15 connected to a stationary crank pin which is eccentric to the axis of rotation. Each set of cylinders comprises a plurality of cylinders, some of which are power producers and some compressor or pump cylinders. These cylinders are radially disposed 20 about a central axis. The air or gas induced by the compressors, is supplied under pressure to the power cylinders substantially at or just prior to the completion of the outward or ascending piston stroke. 25 After expansion which takes place upon the inward or descending stroke of the working pistons, the burned gases are exhausted through valves in the head of the cylinders by centrifugal force. The exhausting of the 30 burned gases is aided by scavenging air which is admitted through cowls or hoods disposed over one or more of the exhaust valves. The engine thus operates upon a 35 two-stroke cycle. The volume of compressed gas contained in the clearance actually existing in the power cylinders may be supplemented by the discharge of the compressors and the clearance volume of the 40 power producers is not confined to the given ratio to the stroke volume but may be at any volume desired and at any ratio, more or less, as desired.

According to the present invention a plurality 45 of power producers revolve upon a central axis, the pistons being connected to a stationary crank pin which is eccentric to the axis of rotation. One or more sets of radial cylinders may be provided if desired. The gases are admitted through 50 mechanically operated valves which rotate around a common cam and are opened at the desired time to admit the charges. Mechanically operated exhaust valves, and 55 preferably a plurality of them, are situated in the head of the cylinder and rotate

around a stationary cam which operates the opening and permits the closing at the desired angular degrees. The valves are mainly maintained closed by centrifugal forces but when opened the exhaust gases are expelled by centrifugal force, by reason of their weight. Over all, or some, of the exhaust valves, cowls, hoods or venturis are fixed with their opening in the direction of rotation and through these the cylinders receive a blast of air induced by their own rotation.

A centrifugal compressor driven by the engine or by any other means, delivers fresh 70 charges under pressure to each power producer, preferably through a common circumferential duct, from which it is admitted to the working cylinders in turn through the inlet valves. Situated between 75 the centrifugal compressor and the duct or pipes may be a carbureter attached to a rotary distributor. The centrifugal compressor induces free air and compresses it through the choke pipe of the carbureter 80 forming the required mixture which is admitted into the working cylinders.

The Diesel two cycle may also be employed in the which case free air is compressed by the centrifugal compressor and 85 admitted into the cylinders and the fuel injected in the usual way after closure of the inlet valves.

The clearance volume in the working cylinders is not confined to the given ratio of 90 the stroke volume and may be at any volume desired either supplemented by the compressor or decreased.

Ports may be supplied at the base of the cylinder, so that they are uncovered by the 95 piston when it has nearly completed the descending stroke and the blast of air entering through the cowl or hood may complete the discharge of foul gas through such ports instead of through the remaining exhaust valves, if so desired, or it may discharge through the remaining exhaust valves.

The invention may be applied to internal combustion engines for aircraft in which the 105 factor of reduced weight per horse power is of importance, it is also applicable to marine engines and the like, in which possible restriction of space presents advantages. The introduction and use of a centrifugal compressor is of especial utility where 110 speed of rotation is maintained nearly con-

stant, as it permits of all the radial cylinders being power producers and materially decreases the ratio of space and weight to power.

5 The centrifugal compressor may revolve at the same speed as the power producers or it may be driven by gears at a higher or lower speed, or it may be driven by a train of gears to permit of varying the ratio 10 of speed. The body of the compressor may rotate in the opposite direction of the fans and in the same direction as the cylinders and may be employed as the distributor of the charges to the cylinders.

10 In the drawings:

Fig. 1 is a part section and part elevation diagrammatic view of my engine.

Fig. 2 is a vertical sectional view of the engine and compressor.

20 In Fig. 1, the cylinders of which five are shown are set radially round the shaft "e" and "b" the piston connected by the rod "c" to the stationary crank pin "d". "P" is the body of a centrifugal compressor held stationary on foundation "Y"; the fans p^1 (Fig. 2) are driven by the gear "r" off the engine shaft "e I"—"f" is the exhaust valves—two being shown and "O" is a cowl or hood over one of them. "X" is the gas duct 30 which transfers the charges through the inlet valve "L".

Fig. 2 is a cross section: "a" the cylinder, "b" piston, "c" connecting rod, "d" crank pin, and "e" the crank shaft held stationary 35 by the holdfast "d". "f" is an exhaust valve operated by cam "k" through the trip rod "h" and lever "g"—"L" the inlet valve operated by the cam "m"—"p" is the centrifugal compressor having its fan or blades 40 driven off the shaft by the gear wheels "r"—"s" is the pipe leading the compressed air to carbureter, "t" to the distributor "v" and thence to the cylinder by the duct "w".

To describe the working of the engine. 45 The radially set cylinders rotate upon a fixed crank shaft and the piston are operated by their connection to a pin set eccentric to the rotation. The engine in its rotation drives a centrifugal compressor, 50 which compresses air through a carbureter, charging it with fuel. At the desired angular degrees the inlet valves of each cylinder opens one at the time consecutively and admits any desired volume of compressed 55 gas and which volume is in ratio to the clearance and compressor capacity or is variable by increasing or decreasing the speed of the centrifugal compressor by altering the gear ratio through a lever. 60 The gases having been admitted and the inlet valve closed prior to the completion of the outward stroke of the piston the gases are ignited, by any means—or in the Diesel cycle compressed air alone would be admitted and combustion made by the admis-

sion of fuel. After ignition expansion takes place forcing the piston inward and thus causing the cylinders to rotate. At or about the end of the inward stroke, the exhaust valves are mechanically opened and the first 70 gases discharged by their own pressure, and a completer discharge by the heavier than air carbon dioxide being thrown out by the centrifugal force due to the high peripheral speed of the engine, and the valves being on such periphery; the complete discharge 75 is then performed by a current of air passing through a scoop or cowl or hood or venturi placed over one or more of the exhaust valves directing the current of air 80 caused by the rotation of the cylinders into the cylinder and out of the other exhaust valves or out of the ports uncovered by the piston at the end or near the end of its stroke. The exhaust valves are then released 85 and reseat themselves, due to the centrifugal force of the rotating cylinders. The cylinders are now ready for a fresh charge and the inlet valve reopened to permit of a repetition of the functions described above 90 operating every revolution.

It is to be understood that the invention is not limited to the exact details herein specifically described but can be practiced 95 in other ways without departure from its spirit.

I claim:

1. In an internal combustion engine, a plurality of rotating cylinders adapted to receive explosive mixture in a precompressed state and to derive energy from said gases by their expansion when ignited, said cylinders being adapted to directly expand said gases without further substantial compression therein, a centrifugal compressor 100 having vanes adapted to be driven upon the rotation of said engine cylinders for compressing air for the said mixture, and means for supplying said gases to said cylinder from said compressor.

2. In an internal combustion engine, a centrifugal compressor rotary engine power cylinders having provision for driving said compressor and receiving explosive mixture therefrom in a precompressed state, said power cylinders having provisions for expanding said explosive mixture upon ignition without substantially further compressing the gases in said engine cylinders, said cylinders having valve means therein so timed as to prevent said further substantial compression of gas therein, said valve means being adapted to permit the cylinders to be scavenged of foul gases after the expansion strokes by means of centrifugal force exerted upon the foul gases by the rotation of the engine cylinders.

3. A rotary internal combustion engine comprising a plurality of rotating cylinders, a centrifugal compressor having a

tionary casing and fan vanes adapted to be driven by said cylinders, a rotary distributor for receiving the gases from said compressor, ducts connecting said distributor with said cylinders for supplying compressed gases thereto and means for admitting the compressed gases to the cylinders at substantially the end of the outward piston strokes whereby there is substantially no further compression of the gases in the cylinders.

4. A rotary internal combustion engine comprising a plurality of rotating power cylinders, a centrifugal compressor having a stationary casing and fan vanes adapted

to be driven at high speed by the rotation of the power cylinders, a conduit upon the discharge side of said compressor adapted to receive compressed air therefrom, a carburettor in said conduit through which all of the compressed air is adapted to flow, a rotary distributor connected with said conduit on the discharge side of said carburettor and ducts connecting said distributor with said engine cylinders for supplying mixture thereto.

In testimony whereof I hereunto affix my signature.

DANIEL MICHEL WEIGEL.
